(57) CLAIM

The ornamental design for a vending machine part, as shown and described.

DESCRIPTION

FIG. 1 is a front elevation view of a vending machine part showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is another perspective view thereof.

The broken lines of FIG. 9 depicting a male grip represent environmental structure that forms no part of the claimed design. The remainder of the broken lines depict portions of the vending machine part that form no part of the claimed design.
